C. E. MILLER.
COMBINATION BUNG AND FAUCET.
APPLICATION FILED AUG. 16, 1915.
1,168,323.

Patented Jan. 18, 1916.

UNITED STATES PATENT OFFICE.

CARL E. MILLER, OF WINNETKA, ILLINOIS, ASSIGNOR TO PRESSED STEEL TANK COMPANY, OF WEST ALLIS, WISCONSIN, A CORPORATION OF WISCONSIN.

COMBINATION BUNG AND FAUCET.

1,168,323.

Specification of Letters Patent. Patented Jan. 18, 1916.

Application filed August 16, 1915. Serial No. 45,610.

To all whom it may concern:

Be it known that I, CARL E. MILLER, a citizen of the United States, residing at Winnetka, in the county of Cook and State 5 of Illinois, have invented certain new and useful Improvements in Combination Bungs and Faucets, of which the following is a specification, reference being had to the accompanying drawing, forming a part 10 thereof.

The main objects of this invention are to produce a combined bung or stopper and tapping faucet for barrels, shipping receptacles and the like, without easily detachable parts which are liable to be mislaid or lost; to provide a tight closure which projects but a short distance from the receptacle, will not be in the way or liable to be broken or displaced when the device is adjusted for use as a bung or stopper for storage, transportation or handling of the receptacles; to facilitate drawing the contents from the receptacles when the device is adjusted for use as a faucet; to prevent unauthorized removal of the device from the receptacle; and generally to simplify and improve the construction and operation of devices of this class.

It consists in the construction, arrangement and combination of parts as herein-after particularly described and pointed out in the claims.

In the accompanying drawing like characters designate the same parts in the several figures.

Figure 1 is a longitudinal section of a combination bung and faucet embodying the invention, showing the device adjusted for use as a bung or stopper; Fig. 2 is a similar view showing the device adjusted for use as a faucet; Fig. 3 is a cross section on the line 3—3, Fig. 1; Fig. 4 is a cross section on the line 4—4, Fig. 1; Fig. 5 is a cross section on the line 5—5, Fig. 2; and Fig. 6 is a longitudinal section of a modification of the device.

In Figs. 1 and 2 the device is shown as applied to a metal barrel *a*, having an outwardly pressed boss *b*, for the bung hole, in which is fitted and secured an internally threaded metal bushing *c*, but it is applicable with little or no change, to other kinds of receptacles, for various purposes, which have bung bushings integral therewith or separately formed.

With barrels and other receptacles for shipping oil and other liquids, it is customary to furnish faucets with such receptacles to take the place of the bungs or stoppers which are used for shipping, for convenience in drawing off their contents when the receptacles reach their destination. The faucets are objectionable as closures for shipping because they project from the receptacles, are in the way and are liable to be broken off or opened accidentally or otherwise. Separate or interchangeable bungs or stoppers and faucets are also inconvenient, as it involves trouble to change from one to the other for tapping the receptacles, and the parts which are not in use are liable to be detached, misplaced and lost.

The present device comprises an externally threaded hollow bung or stopper *d*, which is preferably made of metal and is fitted to screw into and out of the bushing *c* of the barrel or other receptacle. At its outer end which is closed, the bung or stopper is formed with an enlarged head *e*, 75 preferably of polygonal form, as shown in Fig. 5, to receive a wrench for screwing the bung or stopper in and out of the bushing and forcing the head tightly against its seat on the bushing. Between the head and bushing the bung is provided with a packing washer *f*, of leather or other suitable material, for insuring a tight joint when the bung is screwed into the bushing and closed. At an intermediate point in one side the 80 bung is formed with a discharge port or opening *g*, and between this port or opening and the head *e*, with a transverse slot *h*, preferably on the opposite side of the bung from the port *g*. A hollow valve plug *i*, 85 closed at its outer end and open at its inner end, is fitted to turn in the bore of the bung or stopper *d*, and is formed in one side with a lateral port *j*, arranged to be turned into and out of register with the port *g*. It is 90 also formed adjacent to its outer end with one or more, preferably a series, of radial sockets or holes *k*, which register with and are accessible through the slot *h*, when the bung is turned out of the bushing *c* sufficiently to expose the slot.

The outward pressure of the contents of the barrel or receptacle tends to hold the valve plug tightly against its seat in the closed end of the bung, but other provision 105

is made for confining the plug in place in the bung or stopper. Different means may be employed for this purpose. As shown in Figs. 1 and 2, a ring 1 is threaded in the 5 inner end of the bung, and between this ring and the inner end of the valve plug, a spiral spring *m* is interposed, which presses and holds the plug yieldingly against its seat in the closed end of the bung. In 10 place of this ring and spring, a screw *p* may be threaded radially in the bung next to the inner end of the valve plug for holding it in place, as shown in Fig. 6, the outward pressure of the contents of the barrel 15 or receptacle being sufficient to press and hold the plug tightly against its seat, and when it is necessary, to prevent leakage between the plug and bung.

To prevent accidental or unauthorized removal of the bung or stopper from a barrel 20 or other receptacle, the bung is provided adjacent to its inner end with a key or locking piece, which may consist of spring wire *n*, bent inwardly at the ends into open rings 25 or loops which are adapted to project normally through slots *o* in the opposite sides of the bung sufficiently beyond the outer side thereof to engage with the bushing *c* and prevent the removal of the bung from the barrel 30 or receptacle. This key or locking piece may be sprung inwardly for inserting the bung in the bushing or removing it therefrom by means of special pliers having long slender angular bits adapted to be inserted through 35 the lateral ports *g* and *j* when they are in register with each other and exposed outside of the bushing *c*, and to engage with the inwardly bent ends of the key.

In the operation of the device for handling and shipping barrels or other receptacles provided therewith, the bung is screwed into the bushing till its head *e* with the packing washer *f* is seated tightly against the outer face of the bushing, as shown in 40 Fig. 1, thus forming a tight closure which projects but a short distance from the bushing, is not in the way to interfere with the handling, storage or transportation of the barrel or other receptacle, and is not liable 45 to be broken, opened or displaced. When it is desired to tap the barrel or receptacle for drawing off its contents, the bung or stopper *d* is screwed out of the bushing into the position in which it is shown in Fig. 2, 50 thereby uncovering the port *g* and slot *h*, the former being located on the under side and the latter on the upper side of the bung. With a pin, nail or the like, inserted through 55 the slot *h* in one of the sockets or holes *k*, the valve plug *i* may then be turned so as to carry the lateral port *j* therein into and out of register with the port *g*, thereby opening and closing the device, which thus 60 serves as a faucet.

65 It will be observed that the device has no

loose or detached parts which are liable to be misplaced and lost.

Various changes other than those mentioned, in the construction and arrangement of parts of the device, may be made without 70 departure from the principle and scope of the invention as defined in the following claims.

I claim:

1. The combination with a threaded bung 75 bushing, of an externally threaded hollow bung fitted therein and having a lateral port and a transverse slot, and a hollow valve plug fitted to turn in said bung and having a lateral port arranged to be turned into 80 and out of register with the port in the plug, and a radial hole accessible through the slot in the bung.

2. The combination of an externally threaded hollow bung open at its inner end 85 and closed at its outer end which is formed with a head and having a lateral port and a transverse slot, and a hollow valve plug closed at its outer end and open at its inner end rotatably fitting in the bung and having a lateral port arranged to be turned into 90 and out of register with the port in the bung, and a radial hole accessible through the slot in the bung.

3. The combination of an externally 95 threaded hollow bung open at its inner end and closed at its outer end which is formed with an enlarged polygonal head and having a lateral port and a slot in different transverse planes, a hollow valve plug fitted 100 to turn in the bung and having a lateral port arranged to be turned into and out of register with the port in the bung and a series of radial holes accessible through said slot, and means for confining the plug in the bung. 105

4. The combination with an internally threaded bung bushing, of an externally threaded hollow bung fitted therein and formed with a lateral port and transverse slot and with an enlarged head at its outer 110 end, a packing washer between the head and bushing, and a hollow valve plug fitted to turn in the bung and having a lateral port arranged to be turned into and out of register with the port in the bung, and a series 115 of radial sockets accessible through said slot when it is exposed outside of the bushing.

5. The combination with an internally threaded bung bushing, of an externally 120 threaded hollow bung fitted therein and formed with a lateral port and at its outer end with an enlarged closed head, a hollow valve plug fitted in the bung and formed with a lateral port arranged to be turned into and out of register with the port in the 125 bung, and a contractile spring key projecting normally outward through openings in the bung adjacent to its inner end and adapted by engagement with the bushing to prevent the removal of the bung therefrom. 130

6. The combination with an internally threaded bung bushing of an externally threaded hollow bung having openings in opposite sides adjacent to its inner end and
5 a contractile spring key projecting normally through said openings beyond the outer side of the bung.
7. The combination of a hollow bung having a lateral port and adjacent to its inner end openings in opposite sides thereof, a hollow plug valve fitted in the bung and having a lateral port arranged to be turned into and out of register with the port in
10
- the bung; and a contractile spring key projecting normally through the openings in 15 the sides of the plug and having inwardly bent ends which are accessible through said ports when they are in register with each other.
- In witness whereof I hereto affix my sig- 20
nature in presence of two witnesses.
- CARL E. MILLER.
